UNITED STATES PATENT OFFICE.

HEINRICH BOLTSHAUSER, OF ZURICH, SWITZERLAND.

CONDENSING PLANT FOR VEHICLES.

Application filed May 15, 1926, Serial No. 109,442, and in Switzerland May 28, 1925.

This invention relates to a condensing plant for vehicles in which cooling water trickles over the tubes of a surface condenser while, at the same time, cooling air plays over them, and in which a water-jet ejector is provided for extracting the air from the condenser. The invention consists in causing the water which operates the ejector, and as such circulating cooling water is used, to trickle over the condenser directly after it leaves the ejector. Thus, in a manner known per se, the invention renders a single pump sufficient for circulating the cooling water for the condenser and the water for working the water-jet ejector, while, at the same time, it secures the advantage that such circulating pump has only to produce a comparatively small head of water, as large quantites of water are available for the ejector.

The accompanying drawing shows diagrammatically, by way of example, two constructional forms of the invention.

Fig. 1 shows partly a side elevation and partly a longitudinal section of a booster tender having a driving steam turbine in which all the water supplied by a circulating pump is used for operating the water-jet ejector, whilst

Fig. 2 shows a modification in which only a portion of said water is sent through the ejector, some of the parts shown in Fig. 1 being omitted in this second figure for the sake of clearness.

In the figures, 1 is a steam turbine, which, through transmission gearing 2, drives a lay shaft 3, from which the power is transmitted through the well known arrangement of parallel crank and coupling rod 4, to the driving wheels 5. 6 is a surface condenser constructed on the counter current principle: in this condenser, steam is condensed in tubes by water being allowed to trickle and air to flow in opposite directions over the said tubes. The cooling water which is made to trickle over the condenser 6 is circulated by a pump 9 and serves, at the same time, as the water for operating an ejector 12. This latter is provided for the purpose of extracting air from a chamber 16 of the condenser 6. This chamber 16 is connected

by a pipe 13 to the ejector 12. The water which works this ejector trickles, after it leaves the pressure pipe 14, directly over the surface condenser 6, being there brought into intimate contact with air drawn through between the condenser tubes, from the bottom upwards, by exhaust fans 15, and thus it is subjected to a strong cooling action by reason of the evaporation which takes place. 60 The water which trickles over the condenser 6 collects in a tank 10, whence it is again drawn by the pump 9 to repeat its cycle.

Instead of using in the manner shown in Fig. 1 all the water supplied by the pump 9 for operating the ejector 12, only a portion of this water may be sent through the said ejector. Fig. 2 shows such an arrangement in which only a portion of the water supplied by the pump 9 flows through a conduit 19 into the ejector 12 whilst the remaining portion flows through a conduit 17 directly into a pipe 18 distributing it over a portion of the condenser 6.

I claim:

1. In a condensing plant for vehicles, in combination, a surface condenser, means for distributing the cooling water to trickle over the said surface condenser, means adapted to convey the cooling water to said distributing means, and a water-jet ejector for extracting the air from the condenser operated by cooling water and so arranged that the cooling water trickles over the condenser directly after it leaves the ejector.

2. In a condensing plant for vehicles, in combination, a surface condenser having tubes, means for distributing the cooling water to trickle over the tubes of said surface condenser, a pump for circulating the cooling water to said distributing means in a continuous cycle, and a water-jet ejector for extracting the air from the condenser operated by cooling water and interposed between said pump and said distributing means so that the cooling water trickles over the condenser directly after it leaves the ejector.

In testimony whereof, I have signed my name to this specification.

HEINRICH BOLTSHAUSER.
